UNITED STATES PATENT OFFICE.

JAMES B. MARTIN, OF GRAND RAPIDS, MICHIGAN.

COMBINED SCALPER AND GRADER.

SPECIFICATION forming part of Letters Patent No. 473,425, dated April 19, 1892.

Application filed July 6, 1891. Serial No. 398,586. (No model.)

To all whom it may concern:

Be it known that I, JAMES B. MARTIN, a citizen of the United States, residing at Grand Rapids, in the county of Kent and State of Michigan, have invented certain new and useful Improvements in a Combined Scalper and Grader; and I do hereby declare the following to be a full, clear, and exact description of the invention, such as will enable others skilled in the art to which it appertains to make and use the same.

My invention relates to improvements in machines used for the gradual-reduction process of making flour, and more particularly the break-scalper patented to me November 12, 1889, No. 415,050; and the object of my invention is to provide such machines with certain new and useful features hereinafter more fully described, and particularly pointed out in the claims, reference being had to the accompanying drawings, in which—

Figure 1 is a vertical section on the line X X of Fig. 2; Fig. 2, a plan view of the device embodying my invention, having the feed mechanism and cover removed; Fig. 3, a detail of the spring-rolls K, and Fig. 4 a detail showing a portion of each sieve G G.

Like letters and numerals refer to like parts in all the figures.

30 A is the case of the machine, B the outer sieve-frame journaled near its upper end on the boxes C' of the driving-shaft C and suspended at its lower end by a cord D', wound upon a drum D.

35 E is the inner sieve-frame suspended within B by springs F, having the sieves G G of differing grades.

40 W W are sprocket-wheels, S the sprocket-chain, and T the brush for cleaning the lower sieve, and U skids to support the brush.

H is a shaft journaled on the outer sieve-frame, driven from the shaft C by suitable pulleys and belts and provided with multiple cams I I, which cams engage posts J J, attached to the inner sieve-frame E, to vibrate the same, which frame is also provided near its lower end with vertically-flexible springs M, parallel with the upper edges of its sides and normally a short distance therefrom.

45 The free ends of said springs are provided with weights N, which strike against the frame E and jar the same, which aids to keep

the sieves clear and improves their operation. Beneath the lower end of each sieve G and journaled upon the outer frame B are spring-rolls K K, on which are wound aprons L L. The lower edges of these aprons are attached to the upper edges of the respective partitions or walls of the discharge-flues 9 and 10. These aprons are automatically adjusted by the spring-rolls as the sieve-frames are raised and lowered and serve to cut off air-currents and direct the stock from the respective sieves to the respective flues.

55 O is a fan mounted on the shaft O' and enclosed in the cylindrical case P, having a peripheral inlet along its entire length, the exit-opening of which case connects with the semi-cylindrical dust-separator Q, beneath which are two vertical flues, at the bottom 60 of which is the conveyer R for removing the dust. Both flues 1 and 2 and the setting-chamber 3 connect at the bottom with this conveyer, and the said flues are separated by a flexible apron Y to prevent any downward 65 current of air through flue 2, which is tangential to the separator Q at its upper end to receive the dust, flue 1 being central to the same at its upper end to receive the downward current of air, which, striking the apron 70 Y and inclined side 19 of the conveyer-hopper, is deflected upward into the chamber 3, where it still further parts with the dust, which by the eddy in the air-current (indicated by the upper arrows) is separated therefrom and falls back into the conveyer R. 75 From this chamber 3 the air passes into the pipe 4, which opens into the chamber 5, which cuts said pipe in a vertical plane, said chamber having an upper air-discharge 8 and a bottom dust-discharge 11. Continuing thence 80 said pipe terminates in another chamber 6, similar to 5, having upper opening 7 and bottom opening 13. Both upper openings 7 and 8 are at the side toward the fan O, and have 85 guard-plates 15 and 16 to keep the stock from entering the chambers 5 and 6 and also to prevent upward currents of air. A series of openings or slits in a horizontal plane are made in the walls of the flues 9 and 10 to permit the current of air to pass through the descending stock and return to fan.

90 Beneath the sieves I provide two hoppers 12 and 14 of suitable size, having suitable

bottom openings 12' and 14', and at the apex of the adjacent inclined walls of said hoppers is pivoted the adjustable deflector 17, the upper edge of which may be inclined more or less over either hopper, thus dividing the descending stock at a variable transverse line at pleasure and directing more or less into the respective hoppers. A damper 18 in the pipe 4 serves to check the current and variably apportion the amount of air escaping from the respective openings 7 and 8.

By the described construction I secure a uniform current of air across the entire width of the machine. The air spreads laterally in the chambers 5 and 6 and issues in uniform sheets through the openings 7 and 8. So, also, the dust is effectually removed from the air, the heavier portions being thrown into the flue 2, the lighter portions being removed in the chamber 3, and, finally, still lighter parts falling to the bottom of 5 and 6. So, also, the air is used repeatedly, thus avoiding air-currents and dust in the room in which the machine is located.

What I claim is—

1. In combination with an outer adjustable frame and an inner sieve-frame suspended within the same, cams engaging posts on said inner frame, and springs attached to the inner frame having weights attached, substantially as described.

2. In combination with a sieve-frame vertically adjustable at its lower end and discharge-flues beneath said lower end, spring-rolls journaled on said frame, having aprons wound thereon and attached to the walls of said flues, substantially as described.

3. The combination of a fan and casing having peripheral inlet and outlet, a semi-cylindrical separator, vertical flues connecting at their upper ends to said separator and at their lower ends to a conveyer, a chamber adjacent to said conveyer, and an air-pipe extending from said chamber to a point beneath the sieves and opening into transverse chambers having return discharge-openings, substantially as described.

4. The combination of inclined sieves, vertical flues beneath the lower ends of the same

having horizontal transverse slits, a fan having a case having a peripheral inlet-opening connected to said slits and a peripheral discharge-opening connected to a semi-cylindrical dust-separator, a vertical flue from the periphery of said separator and a vertical flue from the axis of the same, an air-passage connecting the lower ends of said flues with chambers beneath said sieve, having discharge-openings opposite the inlet-opening of the fan-case, substantially as described. 60

5. In combination with a fan, a case having peripheral inlet and outlet, a semi-cylindrical dust-separator having a tangential flue and an axial flue parallel to the same, said flues connecting with a conveyer at their bottom and separated by an apron, and a chamber connected with the latter flue and the conveyer, and air-passages leading from said chamber in a closed circuit beneath the sieves to the said fan-casing; substantially as described. 65

6. The combination of a sieve-frame adjustable at its lower end, flues beneath the lower end of the same having horizontal slits, spring-rolls and aprons connecting the walls of said flues and said sieve-frame, a fan and dust-separator at one side of said flues, chambers at the other side of said flues having air-outlets on their sides toward said flues, and an air-passage from said separator to said chambers, substantially as described. 70

7. In combination with inclined sieves, vertical flues beneath the lower ends of the same having lateral air-passages and hoppers beneath said sieves, an air-chamber between said hoppers, said chambers having openings facing the lateral openings in said flues, a fan, a dust-separator, and an air-pipe from said separator to said air-chambers, having a damper between said chambers, substantially as described. 80

In testimony whereof I affix my signature in presence of two witnesses.

JAMES B. MARTIN.
